US0D1103045S

(12) **United States Design Patent** (10) **Patent No.:** **US D1,103,045 S**
(45) **Date of Patent:** **** Nov. 25, 2025**

(54) **FENDER PANEL FOR AUTOMOBILE**

(71) Applicants: **Hyundai Motor Company**, Seoul (KR); **Kia Corporation**, Seoul (KR)

(72) Inventors: **Ryun-Sang Yoon**, Gangwon-do (KR); **Hong-Sook Yoen**, Incheon (KR); **Hyeon-Sung Kim**, Gyeonggi-do (KR)

(73) Assignees: **Hyundai Motor Company**, Seoul (KR); **Kia Corporation**, Seoul (KR)

(**) Term: **15 Years**

(21) Appl. No.: **29/903,637**

(22) Filed: **Sep. 26, 2023**

(30) **Foreign Application Priority Data**

Jun. 15, 2023 (KR) 30-2023-0022805
